PADDED HORSESHOE CALK

Edward Matthews, Hamilton, Ontario, Canada

Application February 26, 1934, Serial No. 713,059

3 Claims. (Cl. 168—41)

My invention relates to improvements in padded horse shoe calks and the object of my invention is to provide an adjustable resilient pad or calk which is so formed in relation to the standard type of horse shoe, to which it is adapted to be attached, that it can be secured in place upon the shoe under the pressure of its own resiliency.

A further object of my invention is to form the pad of rubber and embed the head portions of a pair of calks therein in such a manner that the shanks of the calks protrude in spaced apart relation and are adapted to be received within a pair of calk shank receiving orifices in the shoe, the shanks being spaced apart in the pad a greater distance than the distance between the shank receiving orifices, so that the pad has to be compressed to move the shanks towards each other until they are spaced apart the correct distance for insertion into the orifices in the shoe.

A further and particular object of my invention is to space the shanks apart a sufficient distance in the pad so that such distance is always greater than the distance between the orifices irrespective of any alteration made to the shoe in fitting it to the horse's hoof, for example, there are a pair of orifices normally provided in the toe portion of the shoe and, if it is necessary to widen the toe portion of the shoe, it is hammered out between the orifices thus moving the orifices apart a greater width than their standard spacing.

Another object of my invention is to utilize the compressed resiliency of the pad as a means for securing the shanks in the shoe orifices, irrespective of whether the tapered shanks are of a size to be freely insertable into the orifices or of a slightly larger size to be driven in as in standard practice.

A further object of my invention is to provide a rubber calk or pad having shanks protruding therefrom, wherein the calk is adjustable to permit the insertion of the shanks in shoe orifices having various spaced apart relations.

A still further object of my invention is to embed sharp hardened steel calks in my rubber pad, wherein the calk edges form part of the tread face, thus enabling the horse to get a grip on icy pavements.

My invention consists of a horse shoe pad formed and arranged all as hereinafter more particularly described and illustrated in the accompanying drawing in which:

Figure 1 is a perspective view of a broken away toe portion of a horse shoe together with one of

my pads held between the jaws of a compression tongs before the pad is positioned upon the shoe.

Figure 2 is a longitudinal sectional view through the heel portion of a shoe showing my pad affixed thereto through the insertion of the calk shanks into its orifices.

Figure 3 is a transverse cross sectional view through the pad and shoe as illustrated in Figure 2.

Figures 4, 5 and 6 are plan views of my pad showing various constructions which I may use for making the centre portions of the pads more easily compressible and,

Figure 7 is a side elevational view of another form of pad wherein a transverse horizontal orifice is provided instead of vertical orifices, as shown in the other figures.

Like characters of reference indicate corresponding parts in the different views in the drawing.

My pads are designed for attachment to the standard type of factory-made horse shoes wherein the shoe, as illustrated in the drawing, is furnished with three pairs of calk receiving orifices, one pair of orifices 10 being furnished in the toe 11 of the shoe and a pair of orifices 12 furnished in each of the heel portions 13 of the shoe. In my invention I furnish three pads 14 formed of rubber or other suitable material in lieu of the usual metallic calks, with the object of deadening the sound of the horse's tread on paved streets.

I preferably form my tapered shanks 15 of substantially the same size as the tapered orifices 12 so that they, while a close fit, are readily insertable thereinto, as illustrated in Figure 2. The portions 16 of the calks as embedded in the rubber pad are preferably of wedge shape diametrically positioned across the enlarged heads 17 of the shanks, so that the portions 16 have the same function as the metal calks.

The portions 16, as illustrated in Figure 2, are of truncated triangular form, so that the sloping end faces 25 form a dovetail bond between the portions and the rubber. By this construction the rubber cannot become detached from the portions 16 as the pad becomes worn down, and the portions 16 forming the metal calks are always surrounded by the rubber. In this way, the steel holds the horse against slipping on ice and the rubber against slipping on the pavement.

For securing my pad in place, I so dimension the pad and its protruding shanks 15 that the distance between the shanks is substantially 55

greater than the distances between the orifices in which the shanks are received. For example, in Figure 1 the distances between the shanks 15 of the toe pad are greater than the distances 5 between the orifices 10. When securing the pad to the shoe, the pad is gripped at its ends and compressed as by the tongs 18. The compression of the pad moves the shanks 15 towards one another until the distance between the shanks approximates the distance between the 10 orifices, at which time the shanks can be inserted into the orifices under hand pressure or the light tap of a hammer. When the tongs 18, or other squeezing element, is removed, the 15 pad, which has been under compression, moves to restore itself to its original length and, in so doing, presses the shanks against the sides of their surrounding orifices, which pressure holds the pad in place on the shoe.

20 As the pads are formed of substantially hard tough rubber to withstand wear, they have a high resistance against compression and, therefore, in order to reduce this resistance to compression without softening the rubber I reduce 25 the cross sectional area of rubber between the shanks. This can be done in a number of ways, as for example, by a plurality of vertical orifices 19 as illustrated in Figures 1 and 2, by a single vertical rectangular orifice 20 as illustrated in 30 Figure 4, by a round vertical orifice 21 as illustrated in Figure 5, or a transverse horizontal orifice 22 as illustrated in Figure 7. In Figure 6, I show the cross sectional area of a pad 23 reduced by the formation of a central waisted 35 portion 24.

In fitting the shoes, it is generally found necessary to alter the width of the shoe to fit the horse's hoof and when this alteration is made at the toe by hammering out or contracting the 40 portion of the shoe between the orifices 10, the distance between the orifices is, of course, altered, and, in view of this, I so design my pads that the protruding shanks are a sufficient distance apart that such distance is always greater than 45 the greatest distance produced between the orifices when the toe is widened. In other words, if the toe of the shoe had to be widened to such a distance that it would not be necessary to compress the pad to insert the shanks, the horse's 50 hoof would really require a larger size of shoe with a correspondingly larger size of pad.

While the preferred embodiment of my invention 55 contemplates the free insertion of my pad shanks into the shoe orifices and the utilization of the compressed pad as the sole means for retaining the pad in place, my compressible pad can also be used in conjunction with shanks which are driven into the shoe orifices as in standard practice. When this is done, the shanks 60 will be retained within the orifices through being driven into place and also by the expansive action of the pad.

I have found that the expansion force of the compressed pad is quite sufficient to retain the

pad in place upon the shoe even under abnormal conditions and, while I have illustrated and described a particular embodiment of my invention, it is to be understood that it is not my intention to limit myself to the specific construction shown and described, as my invention broadly contemplates the utilization of the expansive energy in a compressed rubber horse shoe pad as the means for securing such pad to the shoe.

What I claim as my invention is:

1. A resilient toe cork for horse shoes comprising a compressible rubber pad, a pair of metal members embedded in the rubber pad and having shanks protruding from the latter in spaced apart relation and of a size to be received within a pair of spaced apart orifices in a shoe, the distance between the shanks being greater than the distance between the orifices, and the pad adapted to be compressed longitudinally to move 20 the shanks together into substantially the same spaced apart relation as the orifices for insertion thereinto for causing the compressed rubber pad to exert pressure in opposite directions on the shanks for holding them in the shoe orifices, said rubber pad having an orifice therein 25 for increasing its compressible and stretching characteristics.

2. A resilient toe cork for horse shoes comprising a compressible rubber pad, a pair of spaced apart metal V-shaped corks embedded in the pad and positioned to contact the ground, a pair of shanks formed on the corks and protruding from the pad and of a size to be insertable in a pair of spaced apart orifices in a shoe, 30 the distance between the shanks being greater than the distance between the orifices, and the pad adapted to be compressed longitudinally to move the shanks together into substantially the same spaced apart relation as the orifices for 35 insertion thereinto for causing the compressed rubber pad to exert pressure in opposite directions on the shanks for holding them in the shoe orifices, said rubber pad having an orifice therein 40 for increasing its compressible and stretching 45 characteristics.

3. The combination with a horse shoe having its toe portion provided with a pair of spaced apart sockets, the spacing of which is variable and dependent upon the deformation of the toe portion of the shoe to fit the foot of the horse 50 to which the shoe is to be applied, of a resilient toe cork comprising a longitudinally compressible rubber pad, a pair of spaced apart metal members embedded in the rubber pad and having shanks protruding therefrom and of a size to be received into the sockets in the toe portion of the shoe when the rubber pad is compressed longitudinally, thereby, due to the resiliency of the rubber pad, causing the shanks to exert a 55 pressure on the walls of the sockets for assisting in holding the shanks therein.

EDWARD MATTHEWS.
